S. A. HOLMQUIST

STRETCHER

Filed May 31, 1921.

UNITED STATES PATENT OFFICE.

SVANTE A. HOLMQUIST, OF EAST ORANGE, NEW JERSEY, ASSIGNOR OF ONE-HALF TO
HENRY C. KARLSON, OF HASBROUCK HEIGHTS, NEW JERSEY.

STRETCHER.

Application filed May 31, 1921. Serial No. 473,880.

This invention appertains to a scarf stretcher and it has particular reference to a device for smoothing out wrinkles eventually occurring in the material of which so-called four-in-hand neck-ties are made.

The main object of the invention is to provide an improved device of the character described, capable of removing wrinkles and creases formed in the fabric of a scarf due to the tying thereof, and at the same time retaining its original shape.

Another object is to produce a device of the nature set forth by means of which a tie may be held taut long enough to efface wrinkles therein still without unduly straining the same, so that it will regain its fresh appearance, besides prolonging its usefulness.

A further object is the production of a device of the type specified which shall be convenient to insert into a tie or withdraw therefrom, and permitting adjustment of one side of the latter relatively to the other.

A still further object is the provision in a device of the kind referred to of means whereby interrelative slipping may be prevented between members included in the structure and the tie stretched thereover.

Still another object is to furnish a device of the species mentioned so constructed and arranged that one side thereof may be rendered inoperative to enable insertion into a narrow tie.

An additional object is to supply a device of the class alluded to, composed of few, simple and durable parts, not liable to get out of order, besides amendable to low cost of production, and which may be stored as well as shipped in a container of small compass.

Other objects and advantages of the invention will become apparent as the specification proceeds.

With the aforesaid objects in view, the invention consists of the novel combinations and arrangements of parts hereinafter described in their preferred embodiments, pointed out in the subjoined claims, and illustrated on the annexed drawing, wherein like parts are designated by the same refer-

ence characters throughout the several views.

Generally described, the invention under consideration includes in its organization an expandible frame designed for insertion into the larger end of a four-in-hand necktie and consisting of a pair of converging members held apart by inherent resiliency, being formed with oppositely bowed portions adjacent to the vertex thereof where they are joined together by a single coil or loop. At their free divergent terminals these members are provided with inwardly offset handle parts, and intermediately on the former are located anti-slipping elements serving to prevent interrelative sliding between the frame members and the tie stretched thereover. Between the members extends a central stem the outer extremity whereof constitutes a manipulating grip and is furnished with an eye by means of which the device in its entirety can be suspended from a primary support. Associated with this stem is a guide for the handle portions of the members, capable also of limiting the spreading of the latter. At a predetermined distance from the member's bowed portions which locate the implement relatively to the contracted part of the tie, the central stem is curved in a direction away from the plane in which the members are situated, which curve is disposed so as to come substantially opposite that portion of the tie whereof the knot is formed, the curve being adapted to impose a triangulated stretching effect upon the latter named portion to compensate for bagginess occurring therein. The construction and arrangement is preferably such that one member may be manipulated independently of the other and if desired locked into inoperativeness to permit insertion of the instrument in ties of narrow widths.

The advantages of the invention as here outlined are best realized when all of its features and instrumentalities are combined in the one and same structure, but, useful devices may be produced embodying less than the whole.

It will be obvious to those skilled in the

art to which the invention appertains, upon becoming conversant with the details thereof, that the same may be incorporated in several different constructions. The accompanying drawing, therefore, is submitted merely as showing the preferred exemplification of the invention.

In the said drawing:—

Figure I is a side view of this improved 10 device showing it operatively applied within a tie, the contour of the latter being indicated by dot and dash lines;

Fig. II is an edge view of the device looking from the right-hand side of the preceding figure;

Fig. III is an end view of the tie-stretcher as seen from the bottom of Fig. I; and

Fig. IV is an enlarged transverse section taken on the irregular line IV—IV of the 20 last named figure, looking in the direction pointed out by the arrows thereto appertaining.

Referring now to the said views for a detailed description of the invention, the 25 numerals "11 and 12" designate a pair of members that form the converging sides of a frame adapted for insertion into the larger open end of a socalled four-in-hand tie, which has been denoted by the reference 30 character A. These side members are preferably made of flat-sectioned wire, possessing the necessary resiliency to spread apart after being forced inwardly one towards the other. The narrow outer sides of the said 35 members 11 and 12 are arranged, after insertion within the tie A, to engage the opposite edges of the latter and exert a tensioning strain on the fabric from which it is made, sufficient to smooth out such 40 wrinkles as may occur in the tie's larger or wider end portion.

At the vertex, of the converging members where they are joined to one another, is shown a single convolution of a coil or loop 45 14, the purpose of which is to further augment their inherent flexibility. Adjacent to this coil, the said members are bowed slightly outwardly in a sidewise direction as indicated at 15 and 16, for approximately one- 50 quarter to one-third of their lengths while the remaining portions thereof are substantially straight thruout for the actual working distance, that is, where they contact with the opposite edges of the tie. By reason 55 of their curvature, the said bowed parts 15, 16 are brought into touch with the interior of the tie's contracted or narrowing portion, sooner than if the side members of the stretcher were made merely acutely 60 straight, the object whereof will be more fully hereinafter referred to.

In order to afford a convenient manipulating grip for the operator's hand when inserting the stretcher into a tie or removing it 65 therefrom, the free outer extremities of the

members 11, 12 are provided with inwardly offset handle portions 19, 20 having outwardly bent terminals 21, 22 respectively. From Fig. 1 it will be seen that the connection between the outer and inner ends 70 of the said members and the said handles, consists of reversely curved knee portions 25, 26 respectively, formed integral therewith.

To preclude interrelative sliding movement between the side members of the device and the tie stretched thereover, anti-slipping or friction elements 29, 30 are furnished. In their preferred embodiment, these elements consist of pieces of rubber 80 wherewith the said members are covered on their outer edges a predetermined distance from the knees 25, 26, which distance may be about the same as the inception of the bowed parts 15, 16 away from the coil 14. 85 If desired, the said elements 29, 30 may be composed of short sections of rubber tubing, pushed over the handles, past the knee portions, to the required positions on the members that they are to occupy. At the places 90 on the side members where it has been found most desirable to locate these anti-slipping elements, the former are notched or cut out on their outer edges as at 31, 32, to a depth 95 commensurate with the thickness of the walls of the said elements. This enables the placing of the latter's outer wall surfaces in alignment with the corresponding edges of the members adjoining the same, so that no 100 break of continuity occurs between them which would be liable to cause unevenness in the tie stretched thereover.

Intermediate of the said members 11 and 12 extends a central member or carrying stem 35, one extremity whereof as represented, is anchored to the loop 14, as by means of a hook 36 that takes over the adjacent inner portion of the latter. Commencing opposite a point substantially half-way down the lengths of the members 110 bowed parts 15, 16 to a transverse line intersecting approximately the middle of the elements 29, 30, the said carrying stem 35 is curved outwardly to one side, as indicated at 38. When the appliance is entered into a tie or scarf, the said bowed parts 15, 16 encounter the contracted portion of the latter, which thereby prevents further insertion. At such time, the curved part 38 becomes located opposite the portion of the tie from which is formed the knot usually appearing in front, between the corners of a collar. As this portion of the tie is subjected to severe usage, when the same is tied or untied, more wrinkles and creases 120 appear therein than in the remainder of its length, and it also becomes considerably baggy at this point. However, by reason of the fact, that the said knot portion of the tie not only is passed over the curved 125 130

part 38 but is also exposed to sidewise tension by the spreading action of the members 11, 12, a three-sided stretching effect is produced thereon, which removes the creases and smoothes out all wrinkles occurring in the fabric composing the tie. The method followed is seen to best advantage in Fig. IV, wherein the reference letter B designates the tie's rear portion. From this view it will be observed that the bagginess previously mentioned has been taken care of by transferring it to the rear portion of the tie which is made to pass over the curve 38 of the stem 35. Thus, the original width of the tie's front portion is kept the same, while any occurring slackness is taken up in the rear thereof. It is to note that when a tie is new and fresh, the same may be readily tied into a presentable knot without having a great deal of strain applied thereon. But, after some wear, when wrinkles begin to appear therein, more tension is required, which in turn accentuates the creases and makes it still harder to obtain a neat looking knot, why the longer a tie is worn, the more tugging is needed to eradicate the bulging effect observed in worn neck-wear. This finally necessitates discarding of the tie or scarf, altho those parts thereof that lie beyond its knot portion, may be in fair condition. This is because the fabric where the wrinkles have been permanently formed, has been stretched beyond endurance, and cracks or tears have begun to appear therein.

By reason of the fact that with the present instrument, the tie is prevented from creeping down the tapering edges of the side members 11 and 12, due to the anti-slipping elements 29, 30, the tie will remain in the position where it is placed. The lengthwise stretching thereof effected by the operator when drawing the tie over the device is maintained, the same being assisted by the sidewise acting strains, so that the tie is kept taut in all directions, whereby longitudinal, transverse or oblique wrinkles and creases become obliterated.

The central carrying stem 35 is extended as at 40, centrally between the handles 19, 20, being further provided beyond the latter with an eye 41, by means of which the stretcher with the tie thereon may be suspended from a primary support. At 43 and 44 are indicated arms that project in opposite directions away from each other. These arms which constitute a guide for the side members 11, 12 are joined one to the other in the rear by a tie-piece 45 which together with the arms are preferably formed integral with the stem 35 and its extension 40. The outer conjoined extremities of the said arms 43, 44, and the tie-piece 45 constitute stops 47, 48, that are engaged by the inner portions of the handles or grips 19, 20 to

limit the spreading of the side members 11, 12. The space 49 between the arms 43, 44 in front, and the piece 45 in the rear, is sufficiently wide for the handle members 19, 20 to pass each other, were it desired to 70 compress the latter to such an extent.

At 12^a and 20^a (Fig. I) is indicated in dot and dash lines, how one of the side members for instance the right hand one 12, may have its handle portion 20 placed in locking 75 relation with the grip part 40 of the stem 35 by virtue of the bent terminal 22 of the said handle 20 being made to take over the said grip 40 as denoted at 22^a. In view of this arrangement it is possible to contract 80 the device so that it may be inserted into a comparatively narrow four-in-hand tie. On account of being able to manipulate the leg members independently, by merely squeezing on one of the side handles in conjunction with the central grip, either edge 85 of a tie stretched upon this appliance may be adjusted without interfering with the other.

Notwithstanding that this device has been 90 primarily designed for the purpose of distending a tie from the inside thereof in order to eradicate wrinkles occurring in the fabric of which the latter is made, it is manifest that by modifying the shape of its component parts, the same may be used for stretching other articles. 95

While a certain preferred embodiment of this device has been shown and described, it will be understood that changes in the form, 100 arrangements, proportions, sizes and details thereof may be made, without departing from the scope of the invention as defined by the appended claims.

Having described my invention what I 105 desire to secure by Letters Patent and claim, is:—

1. A device of the character described, including exterior members extending in converging relation to each other in substantially straight direction for the greater part of their lengths, being provided near their approaching ends with outwardly bowed portions while their opposite extremities are free, vertex means forming continuations of said portions uniting said members, and another member anchored to said means and extending intermediate of said exterior members constituting together with the latter a manipulating grip for the device, each one 110 of the said exterior members being capable of independent movement towards said other member. 115

2. A device of the character described, including a resilient frame adapted for insertion within an object to be stretched, being composed of a pair of members normally spread apart, in converging relation to one another, said members comprising substantially straight major parts, outwardly 120 125 130

bowed portions conjoined with said parts at the narrower end of said frame, the opposite extremities of the members being free, a vertex constituting an integral convolution 5 flexibly uniting said bowed portions, and a stem central between the latter having one end hooked over said convolution and its other end extending beyond the members, the said convergent members being each capable of independent movement relatively 10 to said stem.

3. A device of the character described, including a frame composed of converging side members free at one end and having a 15 common vertex at the other, being disposed approximately in the same plane, a stem extending from said vertex intermediate of the members permitting the latter independent movement towards one another, and handles projecting in the same general direction 20 from the free ends of said members and offset inwardly therefrom on both sides of said stem.

4. A device of the character described, including a resilient pair of converging members having handle parts in offset alignment therewith, a vertex connecting the approaching ends of the members while leaving the opposite extremities thereof free, a stem extending centrally between the latter from 25 said vertex, reversely curved knee portions connecting said parts in an outward direction with said members, and means for limiting the spreading of the handle parts relatively to said stem, said means reaching out 30 on both sides of the stem and permitting the said parts to be moved towards the same independently one of the other.

5. A device of the character described, including outwardly spreading side members resiliently connected at one end, a stem reaching in central relation between said members from their point of connection to the opposite end, means for limiting the 40 spreading of the members relatively to said stem, the outer edges of said members being provided intermediate the point of connection of the latter and the said means with longitudinally extending cut-out portions, 45 and frictional elements on the members passed across said cut-out portions so as to be countersunk within the same.

6. A device of the character described, including a pair of converging members consisting of flat strips of metal having the narrow edges at one side thereof turned outwardly, the outer edge of each member being provided intermediate the ends of the latter with a notch extending longitudinally 55 thereof, and a soft surfaced frictional element fixedly taking around the member in its said notch, the outer face of said element being flush with the outside edge of said member.

7. A device of the character described,

including oppositely disposed converging members, and friction elements of softer material than said members located thereon flush with their outer edges at a certain distance from the free ends thereof.

8. A device of the character described, including side members extending in convergent relation to each other, being provided with extended notches intermediate their lengths on the outer sides thereof, and sections of tubular rubber elements having their outer portions in said notches.

9. A device of the character described, including oppositely disposed convergent inherently flexible members connected to each other at the converging end, and a sole other member extending longitudinally intermediate said members from their point of convergence but permitting them to be flexed at the opposite end either together or separately towards the said other member.

10. A device of the character described, including a resilient frame composed of converging members free at one end, and a single stem extending substantially centrally 90 from the vertex to the free ends of said members while permitting them to be moved independently towards one another, said stem constituting in conjunction with one of the members handle means for contracting 95 the thereto appertaining side of the device.

11. A device of the character described, including converging side members, a stem extending lengthwise therebetween, and means offset to one side of the plane of said 100 members tending to produce a three-sided stretching effect upon an article drawn over said members.

12. A device of the character described, including side members capable of distending 105 edgewise a tie placed thereover, and a stem member extending lengthwise between the former, said latter member being provided with an outwardly curved portion located approximately midway longitudinally 110 intermediate of said side members so as to come opposite that part of the tie whereof the knot is formed and serving to take up bagginess occurring therein.

13. A device of the character described, including self-spreading side members arranged in convergent relation and having free outer ends, another member reaching substantially centrally from the point of convergence of said side members, and guiding loops extending out from said central member adapted to take around the side members to limit their outward spread.

14. A device of the character described, including outwardly spreading side members 125 resiliently connected at one end, a stem extending in central relation intermediate said members from their point of connection to the opposite end, thereby bisecting the angle between them, and stops integral with said 130

stem serving to limit the spread of the side members by contact therewith.

15. A device of the character described, including converging side members resiliently urged one from the other, a stem extending substantially centrally from the point of convergence of the same, and

loops associated with said stem serving to guide said side members, the outer ends of said loops acting to limit the spreading 10 movement of the side members, the latter being free to pass on either side of the stem.

SVANTE A. HOLMQUIST.
